UNITED STATES PATENT OFFICE

FREDERICK T. FEREDAY, OF ANCHORAGE, KENTUCKY, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed May 27, 1930. Serial No. 455,987.

My invention relates to railway traffic controlling apparatus, and particularly to railway signaling systems employing wayside signals of the semaphore type.

In systems of this character, the semaphore arm is usually biased to a stop position by gravity, and is moved to one or more proceed positions by an electric motor, an electrically controlled holding device being provided to hold the semaphore arm in its proceed position or positions. When the holding device is of the tractive magnet type, it usually requires less current to operate the holding device than to operate the motor. Heretofore, the current for operating both the holding device and the motor has usually been supplied from a primary or a storage battery which had to be renewed or recharged at intervals depending upon the amount of the energy consumed by the signaling apparatus. One object of my invention is to provide means for normally supplying all of the operating current for the holding device and part of the operating current for the motor from an alternating current source through a rectifier, and the remainder of the current for operating the motor from a primary or storage battery, thereby greatly increasing the life of the battery and, in addition, effecting a considerable saving in power consumption.

Another object of my invention is to provide a novel arrangement of apparatus whereby, in the event of an interruption of the alternating current supply, all of the energy for operating the signal may be supplied by the battery.

I will describe one form of railway traffic controlling apparatus embodying my invention, and will then point out the novel features thereof in claims.

The accompanying drawing is a diagrammatic view illustrating one form of railway traffic controlling apparatus embodying my invention.

Referring to the drawing, the reference characters 1 and 1^a designate the track rails of a stretch of railway track along which traffic normally moves in the direction indicated by the arrow. These track rails are divided

by means of insulated joints 2, into a plurality of track sections, only one of which A—B is shown in the drawing. Section A—B is provided with a track circuit comprising a track relay C connected across the rails adjacent the entrance end of the section, and a source of current 3 connected across the rails adjacent the exit end of the section.

Traffic over section A—B is controlled by a wayside signal located adjacent the entrance end of the section, and designated as a whole by the reference character S. This signal comprises a semaphore arm 4 biased by gravity to the stop position in which it extends at right angles to the mast 5, as illustrated in the drawing, together with a motor M for moving it to an inclined or caution position in which it is 45° from the stop position, and to a proceed position in which the semaphore arm is 90° from the stop position. The motor M is operatively connected with the semaphore arm through the medium of suitable operating mechanism indicated diagrammatically in the drawing by the dash lines 6, 6^a and 6^b, this operating mechanism including a ratchet wheel 7. Cooperating with the ratchet wheel 7 is a pawl 8, which when held in engagement with the ratchet wheel, operates to hold the semaphore arm in its caution or proceed position. The pawl 8 is biased to such a position that it is normally out of engagement with the ratchet wheel 7, but is movable into engagement with the ratchet wheel by a holding magnet D comprising a winding 9 controlling an armature 10 attached to the pawl 8.

The signal S also comprises three circuit controllers E, F and G which are operated in accordance with the movements of the semaphore arm 4 and which, as here shown, are operatively connected with such semaphore arm through the medium of suitable mechanism indicated diagrammatically by dash lines 6^b and 6^c. The circuit controller E comprises a contact segment 11 and two contact fingers 12 and 13 cooperating therewith. The segment 11 and fingers 12 and 13 are so arranged that when the semaphore arm 4 occupies its stop position in which it is illustrated in the drawing, the segment 11 engages the

finger 12 to close a contact 11—12; when the arm has moved to a short distance beyond the caution position, for example 5°, the segment 11 then engages the finger 13 to close a contact 11—13 which remains closed when the arm is in the proceed position; and when the arm has moved an additional distance of, say 5°, so that the arm is 10° beyond the caution position, the segment 11 moves out of engagement with the finger 12 and opens contact 11—12, this contact remaining open in the proceed position of the semaphore arm. The circuit controller F comprises a cam 14 which cooperates with a flexible contact finger 15 to open a normally closed contact 15—16 when the semaphore arm has moved to its caution position, and to hold this contact open when the semaphore arm is in its proceed position. The circuit controller G comprises a contact 17—18 which is closed at all times except when the semaphore arm occupies its proceed position.

Operating current for the signal S is supplied jointly by a battery H, and by a transformer T through a rectifier R. This rectifier may be of the well known copper oxide variety, the input terminals 25 and 26 of which are connected with the secondary 19 of transformer T through a current limiting impedance X. The primary 20 of transformer T is constantly supplied with alternating current from an alternator O by means of the wires 21 and 22 of a transmission line Q.

The supply of current for operating the signal is controlled primarily by a polarized relay J which is connected with a suitable source of current, such as a battery N, over a pole-changer P and the front contact 27 of track relay C. The pole-changer P may be controlled in any suitable manner forming no part of my present invention. The supply of current for operating signal S is also controlled by an auxiliary relay K and by a power-off relay L. The relay K is included in the circuit for motor M in such manner that this relay will become energized whenever motor M is supplied with current from battery H, as will be explained more fully hereinafter. Relay L, as here shown, is of the well known direct current type commonly employed for signalling purposes but is provided, in addition to the usual operating windings 30 and 31, with two auxiliary windings 28 and 29 which are heavy enough to carry the total output current of rectifier R. The windings 28 and 29 are connected in series with the operating windings 30 and 31 between the output terminals 23 and 24 of rectifier R, and the parts are so proportioned that relay L will be energized except in the event of an interruption in the supply of current to transformer T. A lightning arrester 32 is connected between the common connection of the windings 28 and 31 and the common connection of the windings 29 and 30,

and this lightning arrester acting in conjunction with the choking effect of the auxiliary windings 28 and 29 provides considerable protection for the rectifier against static discharges which might injure the rectifier.

As shown in the drawing, section A—B is occupied by a train W indicated diagrammatically by an axle and a pair of wheels, and track relay C is therefore deenergized. Polarized relay J is also deenergized, the circuit for this latter relay being open at front contact 27 of relay C. Since relay J is deenergized, all circuits for motor M and holding magnet D of signal S are open at the contacts of this relay, and motor M and holding magnet D are therefore deenergized. The semaphore arm of signal S therefore occupies its stop position. Relay K is deenergized. Relay L, however, is energized since its windings 28, 29, 30 and 31 are constantly supplied with current from the output terminals 23 and 24 of rectifier R. Pole-changer P occupies its upper position in which its contacts 33—34 and 35—36 are closed and its contacts 33—36 and 35—37 are open.

In explaining the operation of the apparatus as a whole, I will first assume that train W moves out of section A—B so that track relay C will become energized and will close its front contact 27. Under these conditions, if pole-changer P remains in the position in which it is illustrated in the drawing, relay J will be supplied with current of what I will term "reverse" polarity, so that it will become energized in its reverse direction. Relay J will therefore close its front contacts 38, 39 and 40, but its polar contacts 41—41^a and 42—42^a remain open as illustrated. The closing of front contacts 38 and 39 of relay J will complete a circuit for winding 9 of holding magnet D, so that current will flow from the output terminal 24 of rectifier R, through wire 58, winding 29 of relay L, wire 59, front contact 60—60^a of relay L, wires 61 and 62, front contact 39 of relay J, wire 67, contact 11—12 of circuit controller E, wire 68, winding 9 of holding device D, wires 69 and 55, front contact 38 of relay J, wires 56 and 64, winding 28 of relay L, and wire 65 to terminal 23 of rectifier R. Winding 9 of holding magnet D therefore becomes energized and attracts the armature 10 so that pawl 8 moves into engagement with the ratchet wheel 7. At the same time, a circuit for motor M is completed at front contacts 38 and 40 of relay J, and current flows from battery H through wires 43 and 44, winding 9 of relay K, wires 45 and 46, front contact 40 of relay J, wires 47 and 48, contact 15—16 of circuit controller F, wires 49 and 50, field winding 51 of motor M, wire 52, armature 53, wires 54 and 55, front contact 38 of relay J, and wire 56 back to battery H. It will be observed that relay K is connected in series with motor M in this latter circuit, so that as

soon as this circuit becomes closed, relay K picks up and closes its front contact 57. Another circuit for motor M is then completed which may be traced from output terminal 5 24 of rectifier R through wire 58, winding 29 of relay L, wire 59, front contact 60—60^a of relay L, wires 61 and 74, front contact 57 of relay K, wires 63 and 74, front contact 57 of relay K, wires 63 and 46, front contact 10 40 of relay J, wires 47 and 48, contact 15—16 of circuit controller F, wires 49 and 50, field winding 51 of motor M, wire 52, armature 53 of motor M, wires 54 and 55, front contact 38 of relay J, wires 56 and 64, winding 28 15 of relay L, and wire 65 to terminal 23 of rectifier R. It will be apparent therefore that under these conditions operating current is supplied to motor M jointly from battery H and from transformer T through rectifier 20 R. Motor M therefore operates to move semaphore arm 4 to its caution position. When the semaphore arm reaches its caution position, cam 14 moves into engagement with contact finger 15 and opens contact 15—16, 25 thereby opening both circuits previously traced for motor M, and motor M therefore becomes deenergized. Relay K then also becomes deenergized and opens its front contact 57. The circuit for holding magnet D, however, remains closed so that pawl 8 is held in engagement with ratchet wheel 7, thereby holding the semaphore arm in its caution position.

When the semaphore arm is to be moved to the proceed position, pole-changer P will be reversed to open its contacts 33—34 and 35—36, and to close its contacts 33—36 and 35—37. Under these conditions, relay J will be supplied with current of normal polarity so that relay J now becomes energized in the normal direction and closes its front contacts 38, 39 and 40, and its polar contacts 41—41^a and 42—42^a. Motor M is then again supplied with current from battery H over a circuit which includes the winding of relay K and which passes from battery H, through wires 43 and 44, winding of relay K, wires 45 and 46, front contact 40 of relay J, wires 47 and 66, reverse contact 42—42^a of relay J, wire 70, contact 17—18 of circuit controller G, wires 71 and 50, field winding 51 of motor M, wire 52, armature 53 of motor M, wires 54 and 55, front contact 38 of relay J, and wire 56 back to battery H. Since relay K is included in this circuit, relay K again becomes energized, and closes its front contact 57, thereby completing another circuit for motor M which may be traced from terminal 24 of rectifier R, through wire 58, winding 29 of relay L, wire 59, front contact 60—60^a of relay L, wires 61 and 74, front contact 57 of relay K, wires 63 and 46, front contact 40 of relay J, wires 47 and 66, reverse contact 42—42^a of relay J, wire 70, contact 17—18 of circuit controller G, wires 71 and

50, field winding 51 of motor M, wire 52, armature 53 of motor M, wires 54 and 55, front contact 38 of relay J, wires 56 and 64, winding 28 of relay L, and wire 65 to terminal 23. Motor M therefore operates to move semaphore arm 4 toward its proceed position. When the semaphore arm has moved a short distance past the caution position, contact 11—13 of circuit controller E becomes closed and upon a little additional movement of the semaphore arm toward the proceed position, contact 11—12 opens. When contact 11—13 closes, a circuit is completed for winding 9 of holding magnet D over which current flows from terminal 24 of rectifier R, through wire 58, winding 29 of relay L, wire 59, front contact 60—60^a of relay L, wires 61 and 62, front contact 39 of relay J, wire 72, reverse contact 41—41^a of relay J, wire 75, contact 11—13 of circuit controller E, wire 68, winding 9 of holding device D, wires 69 and 55, front contact 38 of relay J, wires 56 and 64, winding 28 of relay L, and wire 65 to terminal 23 of rectifier R. When contact 11—12 opens, the first circuit for winding 9 including this contact is opened, but since the circuit just traced for winding 9 is now closed, this winding remains energized. When the semaphore arm reaches its proceed position, contact 17—18 of circuit controller G opens and deenergizes motor M. When motor M becomes deenergized, relay K also becomes energized and opens its front contact 57 so that this relay is then restored to its normal deenergized condition. Holding magnet D is still energized, however, due to the circuit which is closed at contact 11—13 of circuit controller E, and the semaphore arm is therefore held in the proceed position.

If a train enters section A—B when the semaphore arm 4 occupies either its caution or its proceed position, the subsequent deenergization of track relay C will deenergize polarized relay J. When relay J becomes deenergized, the circuit for holding magnet D is interrupted at front contacts 38 and 39 of this relay and holding magnet D then becomes deenergized. Pawl 8 then moves out of engagement with ratchet wheel 7, thereby permitting the semaphore arm to return by gravity to its stop position.

If the supply of alternating current to transformer T fails for any reason, power-off relay L will become deenergized and open its front contact 60—60^a and close its back contact 60—60^b. Under these conditions, if relay J is energized in the reverse direction, motor M will be supplied with current from battery H over the circuit including contacts 38 and 40 of relay J in the manner previously described, but when relay K picks up, the closing of its front contact 57, instead of completing the circuit previously traced for motor M including this contact, completes a cir-

cuit for motor M which passes from battery H, through wires 43 and 73, back contact 60—60^b of relay L, and thence over the circuit previously traced for motor M including contact 57 to wire 56, and from wire 56 back to battery H. Furthermore, under these conditions, winding 9 of holding magnet D, instead of being supplied with current from transformer T through rectifier R, is now 19 supplied with current from battery H over wires 43 and 73, back contact 60—60^b of relay L, and thence over the circuit previously traced for winding 9 including contact 11—12 of circuit controller E to wire 56, and from 15 wire 56 to battery H. It will be apparent therefore that under these conditions all of the current for signal S is supplied by battery H. If relay J is energized in the normal direction when relay L becomes deenergized, 20 all of the operating current for motor M as well as the current for winding 9 of holding magnet D will likewise be supplied from battery H, these circuits being obvious from an 25 inspection of the drawing in the light of the foregoing description.

It will be apparent, therefore, that with apparatus embodying my invention, the energy for operating the motor is normally supplied jointly by a battery H and by a source of alternating current through a rectifier, but in the event of a failure in the alternating current source, all of the energy for operating the motor is then supplied by the battery. Furthermore, all of the energy for operating 35 the holding magnet D is normally supplied from a source of alternating current through a rectifier, but in the event of a failure in the alternating current source this energy is supplied by the battery. This arrangement results in a considerable saving of power and greatly increases the life of the battery.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a railway traffic controlling device adapted to be operated by direct current, a source of direct current, a relay, means for at times supplying said device with current from said source of direct current through the winding of said relay, a source of alternating current, a rectifier, and means controlled by said relay for supplying said device with current from said source of alternating current through said rectifier.

2. In combination, a railway traffic controlling device adapted to be operated by direct current, a source of direct current, a relay, means for at times supplying said device with

current from said source of direct current through the winding of said relay, a source of alternating current, a rectifier, and means controlled by said relay and effective when said relay is energized for supplying said motor with current from said source of alternating current through said rectifier.

3. In combination, a railway traffic controlling device adapted to be operated by direct current, a source of direct current, a relay, means for at times supplying said device with current from said source of direct current through the winding of said relay, a source of alternating current, a rectifier, and means controlled by a front contact of said relay for supplying said motor with current from said source of alternating current through said rectifier.

4. In combination, a railway traffic controlling device adapted to be operated by direct current, a source of direct current, a circuit for said device including said source of direct current, a source of alternating current, a rectifier, and means responsive to current in said circuit for supplying said device with current from said source of alternating current through said rectifier.

5. Railway traffic controlling apparatus comprising a signal provided with an operating motor and a holding magnet both designed for operation by direct current, a source of alternating current, a rectifier, means for supplying said holding magnet with current from said source of alternating current through said rectifier, a source of direct current, a relay, means for at times supplying said motor with current from said source of direct current through the winding of said relay, and means controlled by said relay and effective when said motor is being supplied with current from said source of direct current for supplying said motor with current from said source of alternating current through said rectifier.

6. In combination, a railway traffic controlling device adapted to be operated by direct current, a source of direct current, a circuit for said device including said source of direct current, a source of alternating current, a rectifier, a first relay supplied with current from said source of alternating current through said rectifier and arranged to be energized except in the event of a failure of said source of alternating current, a second relay arranged to be energized in response to current in said circuit, means effective when said first and second relays are both energized for supplying said device with current from said source of alternating current through said rectifier, and means effective when said first relay is deenergized and said second relay is energized for supplying said device with current from said source of direct current.

7. Railway traffic controlling apparatus comprising a signal provided with an operat-

- ing motor and a holding magnet both designed for operation by direct current, a source of alternating current, a rectifier, a first relay connected with said source of alternating current through said rectifier in such manner that said relay is constantly energized except in the event of a failure in said source, means controlled by a front contact of said first relay for at times supplying said holding magnet with current from said source of alternating current through said rectifier, a source of direct current, means controlled by a back contact of said first relay for at other times supplying said holding magnet with current from said source of direct current, a second relay, means for at times supplying said motor with current from said source of direct current through the winding of said second relay, means controlled by a front contact of said second relay and by a front contact of said first relay for at times supplying said motor with said current from said source of alternating current through said rectifier, and means controlled by a back contact of said first relay for at other times supplying said motor with current from said source of direct current.
8. In combination, a stretch of railway track provided with a track circuit including a track relay, a signal for controlling traffic over said stretch provided with a holding magnet and an operating motor both adapted to be operated by direct current, a second relay controlled by said track relay, a third relay, a source of direct current, means including the winding of said third relay and a front contact of said second relay for at times supplying said motor with current from said source of direct current, a source of alternating current, a rectifier, means controlled by a front contact of said second relay and a front contact of said third relay for at times supplying said motor with current from said source of alternating current through said rectifier, and means controlled by a front contact of said second relay for at times supplying said holding magnet with current from said source of alternating current through said rectifier.
9. In combination, a stretch of railway track provided with a track circuit including a track relay, a signal for controlling traffic over said stretch comprising a semaphore arm biased to a stop position and capable of assuming a caution or a proceed position, a motor for moving said arm to its caution or its proceed position and adapted to be operated by direct current, a holding magnet for holding said arm in its caution or its proceed position and adapted to be operated by direct current, a first contact controlled by said arm and arranged to be closed when said arm occupies its stop position but to be opened shortly after said arm moves past the caution position toward the proceed posi-
- tion, a second contact controlled by said arm and arranged to become closed shortly after said first contact opens and to remain closed when said arm is in the proceed position; a third contact controlled by said arm and arranged to be closed when said arm occupies its stop position, its caution position, or any position between its stop and its caution position; and a fourth contact controlled by said arm and arranged to be closed at all times except when said arm occupies its proceed position, a manually operable pole-changer, a polarized relay, means controlled by said pole-changer and including a front contact of said track relay for energizing said polarized relay in its normal or its reverse direction, an auxiliary relay, a source of direct current; a first circuit for said motor including said source of direct current, the winding of said auxiliary relay, a first front contact of said polarized relay, and said third contact; a second circuit for said motor including said source of direct current, the winding of said auxiliary relay, said first front contact of said polarized relay, a first reverse contact of said polarized relay, and said fourth contact; a source of alternating current, a rectifier; a third circuit for said motor supplied with current from said source of alternating current through said rectifier and including a front contact of said auxiliary relay, said first front contact of said polarized relay, and said third contact; a fourth circuit for said motor supplied with current from said source of alternating current through said rectifier and including a front contact of said auxiliary relay, said first front contact of said polarized relay, said reverse contact of said polarized relay, and said fourth contact; a first circuit for said holding magnet supplied with current from said source of alternating current through said rectifier and including a second front contact of said polarized relay, and said first contact; and a second circuit for said holding magnet supplied with current from said source of alternating current through said rectifier and including said second front contact of said polarized relay, a second reverse contact of said polarized relay, and said second contact.
- In testimony whereof I affix my signature.
- FREDERICK T. FEREDAY.
